J. S. OECHSLE

TRACTOR ATTACHMENT FRAME

Filed March 19, 1925

Fig. 1.

INVENTOR
Joseph S. Oechsle,
BY Alfred J. Bratton
ATTORNEY

UNITED STATES PATENT OFFICE.

JOSEPH S. OECHSLE, OF PHILADELPHIA, PENNSYLVANIA, ASSIGNOR TO THE METAL-WELD SERVICE CORPORATION, OF PHILADELPHIA, PENNSYLVANIA, A CORPORATION OF PENNSYLVANIA.

TRACTOR-ATTACHMENT FRAME.

Application filed March 19, 1925. Serial No. 16,693.

To all whom it may concern:

Be it known that I, JOSEPH S. OECHSLE, a citizen of the United States of America, residing at Philadelphia, in the county of 5 Philadelphia and State of Pennsylvania, have invented certain new and useful Improvements in Tractor-Attachment Frames, of which the following is a specification.

This invention relates to portable power 10 units embodying a standard type tractor and work utility, and it has more particular reference to supporting frames therefor.

The fundamental object of my present improvements, accordingly, is to provide a 15 supporting framework of the type referred to embodying characteristic features herein-after fully set forth, typically illustrated by the accompanying sheet of drawings, and tersely recited in the subjoined claims.

20 In the drawings:—

Fig. 1, is a side elevation of my novel tractor attachment frame as particularly adapted to a portable asphalt pavement heater for road repairing and making; the 25 utility being outlined in dot-and-dash lines, in order not to conflict with a clear understanding of the present invention.

Fig. 2, is a top plan view of the same.

Fig. 3, is a vertical section taken substantially on the plane indicated by the arrows 30 3—3 in Fig. 1.

Fig. 4, is a fragmentary perspective view later on specifically described.

Fig. 5, is a fragmentary section illustrating a rear bumper assembly and anchoring 35 means hereafter explained.

Fig. 6, is a fragmentary section showing a fire tube support.

Fig. 7, is a broken perspective view of the 40 upper frame assembly; and,

Fig. 8, is further fragmentary perspective view of a portion of the upper framework.

Referring more in detail to the several 45 views a conventional type of tractor is comprehensively indicated by the numeral 9, said tractor having road and steering wheels 10, 11 respectively. A fuel oil tank is indicated at 12, and a fan blower at 13, the latter having an overhead conduit 14, and 50 elbowed down draft extension 15, for the purpose of concentrating the frame from an appropriate burner—not shown—on to the surface being treated. All of the fore-

going parts are briefly referred to by way of better explaining my invention, but do 55 not form any part thereof.

My novel tractor attachment frame now to be described broadly comprises a lower framework 16, and a super-structure or upper framework 17, appropriately secured 60 rigidly together by clamp bolts 18, whereby the said superstructure may be readily detached and the unit adapted for other purposes than the specific one referred to.

The lower framework 16, comprises 65 spaced longitudinal I-beams 19, 20, bolted or otherwise secured together at 21, in stepped relation, and connected together by transverse channels 22, 23, as well as by a stirrup 24, of channel section affording a 70 rigid support for the tractor front suspension pin 24'. These several transverse members 22, 23 and 24, are preferably lock welded to the longitudinals 19, 20, although they may be otherwise rigidly secured in place. Attention is hereby particularly directed to the rear transverse channel 23, as best shown by Fig. 5, which is fitted with a back bumper 25 of channel section which is butted there-against in web to web relation 75 or with the flanges of said bumper outwards. This bumper 25 is also of a length—as best shown by Fig. 2—to adequately protect the fuel tank 12, above referred to. Connecting support for the framework 16, relative to the tractor 9, is also effected by means of clamp members 26, snugly embracing the tractor rear axle housings 27—80 Fig. 2.

Referring now to the superstructure 17, it will be seen, the same comprises spaced longitudinal I-beams 28, rigidly retained in parallel relation at their forward ends by a cross channel 29, appropriately notched out at 30—Fig. 7—and integrally welded thereto. Further, rigid special relation of the I-beams 28, is ensured through the medium of stirrup straps 31, having their ends welded at 32—Fig. 6—to the web and lower flanges of said I-beams. These stirrup straps 31, afford support for the herein-before referred to overhead conduit 14, as will be readily understood without further explanation.

Verticals 33 of I-section, and similar size 105 to the longitudinals 28, are welded at 34, to

the lower flanges of said longitudinals and reinforced against torsional straining by gussets 35 welded at 36—Fig. 8—in place. Braces 37 of I-section, and like size, are 5 similarly welded at 38 and 39, to the longitudinals 28 and verticals 33, respectively, to afford adequate support and rigidity to the outboard forward end of the superstructure 17.

10 Foot-plates 40, are also weldingly attached at 41—Fig. 4—to the lower ends of the verticals 33, and provided with holes 42, for the passage of holding down bolts 43, whereby the superstructure 17 is removably

15 attached on the lower framework 16. The forward foot plates 40, are provided with integral hooks 44, to accommodate anchoring means for the funnel—not shown—of the down-draft extension 15.

20 In addition to the foregoing means, effective to rigidly brace the superstructure 17 against torsional deflection, I weld at their ends 45, intersecting bars or flats 46—Fig. 3—to the web and flanges of the

25 forward verticals 33, the same being also welded together at their point of intersection 47. Plates 48 are welded at 49, to the rear verticals 33, and provided with holes 50, for passage of bolts, whereby said plates

30 are securely clamped to the tractor dash 51—Fig. 1.

A bar or rod 52—Figs. 1 and 2—is anchored at 53, to the superstructure 17, as well as to the rear transverse channel 23, 35 of the lower framework 16; thereby tying said superstructure and framework together and evenly distributing the load.

From the foregoing it is thought the inherent rigidity and obvious advantages of 40 my novel tractor attachment frame will be fully appreciated without further elaboration. Furthermore, the right is reserved to make such detail changes as fairly lie within the scope of the subjoined claims;

45 for example the superstructure 17, may be integrally joined to the framework 16, by welding the verticals 33, to the upper flanges thereof.

Having described my invention, I 50 claim:—

1. A tractor attachment comprising a framework of spaced longitudinal I-beams with integrally welded transverse channels with means for securing said framework to the tractor front suspension and rear axle housings, in combination with a removable superstructure of I-section longitudinals and spaced integrally welded verticals, said longitudinals being connected at the forward end by an interfitted channel section welded thereto, I-section braces welded intermediate the longitudinals and forward verticals, spaced stirrup straps transversely intermediate the longitudinals integrally joined to the lower flanges thereof, foot plates weldingly attached to the lower ends of the verticals, gussets welded at the upper ends of the verticals as well as below the longitudinals intersecting flat bars weldingly connected across the front verticals, plates welded to the rear verticals for clamping attachment to the tractor dash, and means whereby the foot

weldingly attached to the lower ends of the verticals, and means whereby the foot-plates are attached to the framework top flanges.

2. A tractor attachment comprising a framework of spaced longitudinal I-beams with integrally welded transverse channels with means for securing said framework to the tractor front suspension and rear axle 70 housings, in combination with a removable superstructure of I-section longitudinals and spaced integrally welded verticals, said longitudinals being connected thereto, I-section 75 braces welded intermediate the longitudinals and forward verticals, spaced stirrup straps transversely intermediate the longitudinals integrally joined to the flanges thereof, foot plates weldingly attached to the lower ends of the verticals, gussets welded at the upper ends of the verticals as well as 80 below the longitudinals, and means whereby the foot plates are attached to the framework top flanges.

3. A tractor attachment comprising a framework of spaced longitudinal I-beams 90 with integrally welded transverse channels with means for securing said framework to the tractor front suspension and rear axle housings, in combination with a removable superstructure of I-section longitudinals and 95 spaced integrally welded verticals, said longitudinals being connected thereto, I-section braces welded intermediate the longitudinals and forward verticals, spaced stirrup straps transversely intermediate the 100 longitudinals integrally joined to the lower flanges thereof, foot plates weldingly attached to the lower ends of the verticals, gussets welded at the upper ends of the verticals as well as below the longitudinals, intersecting flat bars weldingly connected across the front verticals, and means whereby the foot plates are attached to the framework top flanges.

4. A tractor attachment comprising a framework of spaced longitudinal I-beams with integrally welded transverse channels with means for securing said framework to the tractor front suspension and rear axle 110 housings, in combination with a removable superstructure of I-section longitudinals and spaced integrally welded verticals, said longitudinals being connected thereto, I-section 115 braces welded intermediate the longitudinals and forward verticals, spaced stirrup straps transversely intermediate the longitudinals integrally joined to the lower flanges thereof, foot plates weldingly attached to the lower ends of the verticals, gussets welded at the upper ends of the verticals as well as below the longitudinals intersecting flat bars weldingly connected across the front verticals, plates welded to the rear 120 verticals for clamping attachment to the tractor dash, and means whereby the foot 125 plates are attached to the framework top flanges.

plates are attached to the framework top flanges.

5. A tractor attachment comprising a framework of spaced longitudinal I-beams with integrally welded transverse channels with means for securing said framework to the tractor front suspension and rear axle housings, in combination with a removable superstructure of I-section longitudinals and spaced integrally welded verticals, said longitudinals being connected thereto, I-section braces welded intermediate the longitudinals and forward verticals, spaced stirrup straps transversely intermediate the longitudinals integrally joined to the lower flanges thereof, foot plates weldingly attached to the lower ends of the verticals, gussets welded at the upper ends of the verticals as well as below the longitudinals, intersecting flat bars weldingly connected across the front verticals, plates welded to the rear verticals for clamping attachment to the tractor dash, an anchorage intermediate the superstructure longitudinals and framework rear end, and means whereby the foot plates are attached to the framework top flanges.

6. A tractor attachment comprising a

framework of spaced longitudinal I-beams with integrally welded transverse channels with means for securing said framework to the tractor front suspension and rear axle housings, in combination with a removable superstructure of I-section longitudinals and spaced integrally welded verticals, said longitudinals being connected thereto, I-section braces welded intermediate the longitudinals and forward verticals, spaced stirrup straps transversely intermediate the longitudinals integrally joined to the lower flanges thereof, foot plates weldingly attached to the lower ends of the verticals, gussets welded at the upper ends of the verticals as well as below the longitudinals, intersecting flat bars weldingly connected across the front verticals, plates welded to the rear verticals for clamping attachment to the tractor dash, an anchorage intermediate the superstructure longitudinals and framework rear end, means whereby the superstructure is attached on the framework aforesaid, and a rear bumper of channel section at the end of said framework.

In testimony whereof, I affix my signature the 13th day of March, 1925.

JOSEPH S. OECHSLE.
